UNITED STATES PATENT OFFICE

2,141,962

ABRASIVE DRUM FOR LEATHER SURFACING MACHINES AND THE LIKE

Edgar H. Van Valkenburgh, Gloversville, N. Y.

Application February 2, 1938, Serial No. 188,240

5 Claims. (Cl. 51—194)

The invention relates to abrasive drums.

One object of the invention is to provide an improved clamp for holding sheet abrasive material to an abrasive drum. Another object of the invention is to provide an improved construction for separating the heads in a helical path. Another object of the invention is to provide an abrasive drum structure of rigid construction and capable of operating under high speed and considerable pressure without developing vibration or play in any of the parts. Another object of the invention is to provide a simple construction for abrasive drums of the class indicated which may be manufactured at small cost. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing showing one of many possible embodiments of the mechanical features of this invention,

Figure 1 is an axial sectional view of the abrasive drum constructed in accordance with the invention;

Figure 2 is an end view;

Figure 3 is an end view of a clamping ring on a small scale;

Figure 4 is a plan view of the abrasive paper before application to the drum.

The abrasive drum of my invention may be used on the type of machine shown in my prior Letters Patent No. 1,983,585 or on the type of machine shown in George M. Curtin Patent No. 2,086,516. The abrasive drum of my invention, however, is not limited to use on such machines but may be used also on wood sanders and other machines where a large cylindrical abrasive surface is desired. Accordingly, it is not believed to be necessary to describe any particular machine, especially as the aforesaid patents may be referred to, as well as George M. Curtin Patent No. 2,076,193 describing an abrasive drum for leather surfacing machines in which abrasive paper is strapped taut on the cylindrical surface thereof.

Referring now to Figure 1, there is provided a horizontal shaft 10 constituting the axial shaft for the abrasive drum and which may be journaled in the machine, as shown in my prior patent referred to or as shown in Curtin Patent No. 2,086,516 or in any other suitable manner, and which may be driven in any suitable way, for example as shown in said patents. I further provide a cylindrical drum 11 having an outer cylindrical surface broken only by a spiral groove 11a in which the abrasive material is overlapped. The drum 11 may be made of cast iron or any

other suitable material and is preferably an integral structure. The drum 11 has diametral web portions 12, 12 which are press fitted into the drum and which have hubs 13, 13 keyed to the shaft 10 by means of keys 14.

Journaled in each of the diametral web portions 12 is a stud 15 with which is integrally formed a pinion gear 16. The stud 15 extends outwardly and has a square wrench portion 17. Annular webs 18 having hubs 19 keyed to the shaft 10 by means of the key 14 have journals for the outer or long ends of the studs 15 in alignment with the journals in the web 12, thereby effectively and rigidly holding the studs 15 so that great power may be exerted by the pinions 16.

The pinions 16 mesh with internal ring gears 20 which are press fitted into externally threaded annular members 21 of stepped shape in cross section, as shown in Figure 1. The ring gear 20 fits against a shoulder 22 of the annular threaded member 21 and is to all intents and purposes integral with the annular member 21. The annular members 21 are free to move inside of the drum 11.

At each end of the drum 11 is a head 25 which consists of an annular outer portion having steps as shown in cross section and having an inwardly extending cylindrical portion 26 which is internally threaded and in threaded engagement with the corresponding annular threaded member 21. Each head 25 likewise has a diametral web 27 fitting around the shaft 10 but not secured thereto. Each head 25 is free to move relative to the drum 11. Press fitted into the drum at each end thereof against a shoulder 29 so as to be virtually a part of the drum 11 is a collar 30 having a series of spiral grooves 31 therein. Spiral grooves 32 extending in the same angular direction are formed in the portions 26 of the heads 25 and keys 33 are located in grooves or keyways 31 and 32. As shown, there are four grooves 31 in each collar 30 and four grooves 32 in each inward extension 26 of each head 25 and there is a key 33 between each pair of grooves 31 and 32, there thus being eight keys in all. The key 33 may be tight in either of the grooves 31 and loose in the other one, as desired.

There is an arcuate slot 35 in each of the webs 27 through which an end wrench may be inserted, thereby to turn either of the studs 15 and with it its corresponding pinion gear 16. This action turns corresponding annular threaded portion 21 which moves the corresponding head 27 either inwardly or outwardly, depending on the direction which the stud 15 is turned. The head 25 in question, however, can only move outwardly in a spiral course as determined by the pitch of the grooves 31 and 32 and the keys 33 therein.

This pitch is the same as the pitch of the abrasive paper upon the drum 11.

Extending outwardly from each head 25 is an annular cylindrical portion 36 which is an integral part of head 25. In this outwardly extending cylindrical portion are a plurality of slots 37 large enough to receive a plurality of bolts 38 having heads 39 with sockets 40 for internal end wrenches. Square nuts 41 abut the web 27 and thus the bolts 38 may readily be tightened. Bolts 38 extend through holes in a clamp 42, the heads 39 seating in countersunk portions thereof, as shown. The clamp 42 may be made of steel and in cross section is shaped as clearly shown in Figure 1 with a paper clamping portion 43 and an outer and inwardly extending annular portion 44 which abuts the outer cylindrical surface of the cylindrical extension 36, thereby to exert the thrust of the bolts 38 against the cylindrical portion 36 so that the reacting force will tightly clamp the clamp portion 43 against the paper 45. It will be seen that each part of the clamp 42 acts as a lever and in order that clamping action may be effected, saw cuts 46 and 47 are made in the clamps 42, the saw cuts 46 being on the outside and the saw cuts 47 on the inside and each one extending approximately to the median line of the clamp or about to the plane of the axes of all the bolts 38. These saw cuts are preferably in staggered relation. Thus the clamping rings 42 are integral one piece rings but nevertheless the clamping action may be freely exerted. By reason of the fact that they are flexed inwardly at the several bolts but consist of integral pieces, they follow the contour of the cylindrical surface of the drum 11 very closely and clamp the paper 45 very smoothly thereto.

The paper 45 extends between the clamps and is laid upon the drum 11 in a helical course and overlapped in the groove 11a. Figure 4 shows the shape of the abrasive paper before it is applied to the drum. With the clamps herein disclosed, the paper can be held very tightly to the heads 25 and with the mechanism for moving the heads outwardly in a helical course, the paper can be made very taut and all wrinkles removed. The threads in the annular members 21 and the heads 36 are self-locking so that once the paper is tightened, the parts will not move excepting by the further application of a wrench to the ends 17 of the studs 15.

A particular feature of my invention resides in the fact that the screw threaded members are close to the keyways and the keys therefor, eliminating strain of the parts by putting the guiding means next to the thrusting means. Furthermore, the keyways are in a member which is practically integral with the drum, and the cylindrical portion 32 of the head 25 has a wide bearing surface in the collar 31. End play and side play are thus substantially eliminated and the parts have great strength. The construction, furthermore, is such that the parts may be readily and quickly assembled.

It will thus be seen that there has been provided by this invention an apparatus in which the various objects hereinbefore set forth together with many thoroughly practical advantages are successfully achieved. As many possible embodiments may be made in the mechanical features of the above invention and as many

changes may be made in the embodiment set forth, it is to be understood that all matter hereinbefore set forth or shown in the accompanying drawing is to be interpreted as illustrative and not in a limiting sense. 5

I claim:

1. An abrasive drum construction comprising a metal cylindrical shell, a pair of heads one on each end of said shell, each head comprising a peripheral portion flush with the exterior of said shell and a shouldered portion fitting under said shell and the heads being rotatably mounted with respect to said shell, a central mounting shaft for the drum, hubs mounted on and fastened to said central shaft, studs journalled in said hubs, 10 pinion gears on said studs, ring gears outside of and meshing with said pinion gears, inwardly extending cylindrical flanges integral with said heads, annular members inside of said inwardly extending cylindrical portions but outside of said 20 studs, said annular members being threaded on the outside and in engagement with threads on the flanges, the internal gears being fastened to the annular members, and spiral directing means connecting the flanges and the drum whereby 25 upon turning the studs the heads are moved spirally outwardly.

2. An abrasive drum construction comprising a metal cylindrical shell, means including a spiral slot on the inside of said shell, a head rotatably mounted on said shell having an internal annular portion inside of said means and a peripheral portion, cooperating spiral grooved means on the outside of said annular portion, whereby the head is forced to move spirally with respect to the 30 drum, an annular member inside of the internal annular portion, internal gear means connected to the annular member, a pinion gear meshing with the internal gear, and a stud upon which 35 said pinion gear is formed, the stud being inside of the annular member, the annular portion and the annular member having engaging threads, whereby upon turning the stud the annular member is rotated, thus driving the head outwardly 40 which moves in a spiral path on account of the 45 spiral groove means, and the thrust being close to the spiral groove and spiral groove means.

3. In apparatus as claimed in claim 1, the combination with the parts and features therein specified of annular clamps having portions to 50 engage the peripheries of the heads, and bolt means to press the clamps inwardly against the heads, there being cuts in the clamps to permit them to flex inwardly.

4. In apparatus as claimed in claim 2, the combination with the parts and features therein specified, of an annular clamp having a portion to engage the periphery of the head, there being cuts in the clamp to permit it to be flexed inwardly, and radial bolts secured to the head and passing through the clamp to clamp a piece of 60 coated abrasive material onto the head and thereby position it on the drum.

5. A clamp for an abrasive drum comprising a ring having a portion with an internal cylindrical 65 surface to effect the clamping, holes in said ring on the edge of said portion, bolts extending through said holes radially of the ring, and cuts on either side of the ring to permit it to be flexed inwardly.

EDGAR H. VAN VALKENBURGH, 70
